MOLDING MACHINE CLAMPING APPARATUS

Filed May 31, 1929

UNITED STATES PATENT OFFICE

GIDEON C. BATTEN, OF CINCINNATI, OHIO

MOLDING MACHINE CLAMPING APPARATUS

Application filed May 31, 1929. Serial No. 367,516.

My invention relates to improvements in molding clamping apparatus. One of its objects is to provide improved apparatus to clamp the cope member and drag member of a molder's flask in place upon the mold table of a molding machine just prior to and during the operation of inverting said cope and drag members. Another object is to provide clamping means which is adjustable to clamp the cope and drag members of flasks of different sizes, even where the flask is of equal or greater length than the mold table. Another object is to provide clamping mechanism adapted to be conveniently applied for use and detached after use. Another object is to provide a simple, strong, and reliable clamping means for the purpose intended. My invention also relates to certain details of form and arrangement, and combination of components, all of which will be fully set forth in the description of the accompanying drawings, in which:

Fig. 1 is a side elevation of the mold table of a molding machine with a flask member mounted thereon and with my improved clamping apparatus applied thereto.

Fig. 2 is an end view of Fig. 1.

Fig. 3 is an end view of the opposite end of Fig. 1 from that shown in Fig. 2.

Fig. 4 is a perspective view of one of the clamping members detached.

Fig. 5 is a detail of the clamping lever detached.

The accompanying drawings illustrate one embodiment of my invention in which 15 represents the mold table or board of a molding machine of the general type in which the mold table is attached to the piston of a pneumatic cylinder, or to other mechanism whereby the mold table with a flask member clamped thereto may be lifted and inverted and the flask member deposited upon a plate or bed until required for use in a casting operation. One of the flask members, for instance the cope member 16 is mounted upon the mold table and a mold cavity or impression of the article to be cast is formed in a body of molder's sand or molding material within the flask member, either by mechanical means or a pattern. A lid or plate 17 is then

placed above the flask member 16 and the clamping apparatus is adjusted to position.

The mold table 15 is provided with two T-shaped slots 18 and 19. A pair of detachable brackets 20 and 21, each comprising a vertical section 22 and a horizontal section 23, and connected together by means of a cross bar 24 are adjusted into position by inserting the sections 23 into one end of the T-slots 18 and 19. A pair of detachable brackets 26 and 27 each comprising a vertical section 28 and a horizontal section 29 are adjusted into position by inserting the horizontal sections 29 into the opposite ends of the T-slots 18 and 19. A horizontal shaft 30 is adjusted into relation to a pair of perforations 31 through the upright sections 28 of the brackets 26 and 27, so that said shaft is retained in relation to said brackets 26 and 27 by sliding the horizontal sections 29 into the T-slots 18 and 19 of the mold board. The shaft 30 journals relative to the perforations 31 through bracket sections 28. Mounted loosely or rigidly upon the central portion of the shaft 30 is a sleeve having two cam or eccentric faces 32 and 33 and an intermediate guide or spacing member 34, and an actuating lever 35.

The cross-bar 24 has a centrally located upward projection 36 provided with a series of perforations 37 one above the other. A yoke shaped clamping bar 40 is provided at one end with a tongue 41 adapted to enter any one of the perforations 37, depending upon the height of the flask member 16. The opposite end of the clamping bar 40 is formed into a hook 42 and said hook portion is slit lengthwise of the hook by means of a slot 43. The hook 42 engages beneath the eccentrics 32 and 33, and the guide 34 enters the slot 43 and serves to retain the hook members 42 in engagement with the faces of the eccentrics 32 and 33. Wedge shaped blocks 44 and 45 are preferably employed between the lid 17 and the yoke shaped clamping bar 40 to take up practically all of the slack, while the balance of the slack is taken up by means of the eccentrics which are partially rotated relative to the hooks 42 by means of the actuating lever 35, to firmly clamp the flask member.

in position upon the mold table until the mold board flask member and clamping apparatus have been inverted in position and the lid 17 deposited upon a firm supporting member after which the clamping apparatus is detached and the mold table returned to its original position ready to receive another flask member.

The shaft 30 and eccentrics 32 and 33 are adapted to be supported by any desired pair of perforations 31, and the tongue 41 to be engaged with any one of the perforations 37, thereby giving the clamping apparatus a wide range of adjustability vertically to accommodate flask members of different sizes, while the bracket members 22 and 28 are adjustable to and from each other through a wide range of adjustments. The members 22 and 28 may be adjusted if desired to overhang the ends of the mold table so that flask members the full length of the mold table may be employed if desired. A series of yoke members 40 of different lengths are provided, each adapted for use with flask members of approximately the same length.

The apparatus herein shown and described is capable of considerable modification within the scope of the claims without departing from the spirit of my invention.

30 What I claim is:

1. Molding machine clamping apparatus comprising an invertible molding table provided with substantially parallel T-slots, a first pair of brackets detachably attached to said T-slots at one end thereof, a second pair of brackets detachably attached to said T-slots at the opposite end thereof, and a yoke detachably attached at one end to said first pair of brackets and detachably attached at its opposite end to said second pair of brackets and engaging a flask member intermediate of said first pair and second pair of brackets to clamp the flask member to said molding table.

45 2. Molding machine clamping apparatus comprising an invertible molding table provided with substantially parallel T-slots, a first pair of brackets detachably attached to said T-slots at one end thereof, a second pair of brackets detachably attached to said T-slots at the opposite end thereof, a yoke detachably and adjustably attached at one end to said first pair of brackets and detachably and adjustably attached at its opposite end to said second pair of brackets, and engaging a flask member intermediate of said first pair and second pair of brackets to clamp the flask member to said molding table.

50 3. Molding machine clamping apparatus comprising an invertible molding table provided with substantially parallel T-slots, a first pair of brackets detachably attached to said T-slots to one end thereof, a second pair of brackets detachably attached to said T-slots at the opposite end thereof, a yoke de-

tachably and adjustably attached at one end to said first pair of brackets and having its opposite end forked and formed into a hook, a cross bar carried by and adjustable relative to said second pair of brackets, cam faces carried by said cross bar to engage the hooked end of said yoke, an actuating lever to actuate said cam faces, and adjusting blocks interposed between said flask member and said yoke to take up the major portion of the slack between said flask member and yoke before said actuating lever is actuated to put strain upon said yoke.

55 In testimony whereof I have affixed my signature.
